United States Patent

Des. 238,656

Patented Feb. 3, 1976

238,656

BEVERAGE CONTAINER OR THE LIKE

Leslie Stephan Marco, Des Plaines, Ill., assignor to Illinois Tool Works Inc., Chicago, Ill.

Filed Apr. 29, 1974, Ser. No. 465,021

Term of patent 14 years

Int. Cl. D9—01

U.S. Cl. D9—100

Fig. 1

Fig. 2

FIG. 1 is a perspective view of a beverage container or the like showing my new design; and

FIG. 2 is an elevational view showing the side opposite that seen in FIG. 1.

I claim:

The ornamental design for a beverage container or the like, as shown.
